WATCH STRAP

Emil Lackow, Brooklyn, N. Y.

Application September 25, 1945, Serial No. 618,474

5 Claims. (Cl. 224—4)

1

This invention relates to watch straps, particularly of the type adapted for use with wrist watches.

The conventional form of watch strap consists of two separate strap members, one end of each containing a loop in engagement either with an ear extending outwardly from the wrist watch, or with a spring bar associated with the wrist watch—the other ends of the straps being provided with a buckle arrangement. In attaching this form of watch strap to the wrist, it is generally necessary to hold the watch and strap combination against the body, or to otherwise hold the two strap members between the fingers, while the buckle attachment is being effectuated. This operation is generally inconvenient and difficult to perform, and occasionally results in an inadvertent dropping of the watch. It is within the contemplation of my invention to eliminate this difficulty in applying watch straps to the wrist by enabling the combination of watch and strap members to be readily and easily slipped over the wrist, without the necessity of difficult maneuvering.

With conventional watch straps of the type above mentioned it is generally necessary to temporarily remove the entire watch and strap assembly from the wrist during the washing of one's hands. This is not only an inconvenient operation in itself, but it may result in the loss of a watch when it is placed upon a wash stand and then forgotten, which is not an infrequent occurrence. It is accordingly another important object of my invention to obviate this danger by avoiding the necessity of completely detaching the component parts of the strap assembly, and enabling it to be moved upwardly to a portion of the arm remote from the wrist. And in the accomplishment of this objective, it is a further object to enable a watch strap, which may be made of inextensible material such as leather, to be expanded so that it may be readily moved to the upper part of the arm, or to a point near the elbow.

And it is a further object of this invention to provide an inexpensive and readily fabricated device capable of performing the aforesaid functions.

Other objects, features and advantages will appear from the drawings and description herein-after given.

Referring to the drawings,

Figure 1 is a perspective view of the watch strap of my invention shown in its open condition.

2

Figure 2 is a perspective view of the device of Figure 1 shown in its fully closed condition, and

Figure 3 is a perspective view of the watch strap of my invention shown on an arm in a position remote from the wrist.

In the drawings which show a preferred form of my invention, the essential component parts thereof are the flexible strap member 5, the coacting strap member 6 and the flexible connecting member 7. Members 5 and 6 are provided with loop portions 8 and 9, respectively, and these are mounted over pin bars 10 and 11 associated in conventional manner with the wrist watch 12. Strap member 6 contains the buckle 13 through which the terminal portion 14 of strap member 5 is slidably movable, said terminal portion 14 also being capable of entry within loop 15 attached to the buckle member 6, in conventional manner.

20 The flexible connecting member 7 has attached to the two terminals thereof the loop members 16 and 17, said loop members being slidably disposed over strap members 5 and 6, respectively. The operative slidable movement of loop 17 along buckle member 6 is limited by the watch 12 and the loop 15; and the operative slidable movement of loop 16 is limited by the watch 12 and the raised ornamental stop member 18 secured to the terminal portion 14 of member 5. The thickness of said stop 18 is such that it will extend outwardly beyond the undersurface 19 of loop 16—that is, it is of a thickness sufficient to prevent the loop from sliding off the terminal 14. The thickness of stop 18, however, is less than the height of the opening 19 in the buckle, and less than that of the opening 20 in loop 15, whereby it may readily pass through the buckle and through said loop 15.

In operatively employing this device, the entire 40 assembly is first expanded by slidably moving the loops 16 and 17 outwardly towards terminal 14 and buckle 13, respectively, whereby the combined effective circumference of members 5, 6 and 7 will be sufficient to enable the assembly to be 45 slipped over the hand and to the wrist. Thereafter terminal 14 is passed through buckle 13 and loop 15 in conventional manner to close the strap and enable it to conveniently envelop the wrist. 50 During this operation, the loops 16 and 17 will slidably move along strap members 5 and 6, so that the connecting member 7 will adjustably position itself in proper relation to the wrist and the coacting members 5 and 6, forming a double and reenforced strap arrangement along certain 55

portions of the assembly, as clearly shown in Figure 2.

Should one desire to disengage the strap so as to move it upwardly along the arm to a position remote from the wrist, as would be desirable during the washing of one's hands, all that need be done is to disengage the buckle and expand the assembly in the manner aforesaid, whereby the circumference will be increased to permit the strap to be slidably moved to the position shown in Figure 3.

Although the particular form of my invention illustrated shows both loop members 16 and 17 in slidable engagement with strap members 5 and 6, it is also within the contemplation of my invention to arrange the connecting member 7 with only one slidably loop member such as 16, the other loop member being affixed or anchored in place at a predetermined point.

In the accompanying drawings, the invention has been shown merely by way of example and in preferred form, but obviously many variations and modifications may be made therein which will still be comprised within its spirit. It is to be understood, therefore, that the invention is not limited to any specific form or embodiment, except insofar as such limitations are specified in the appended claims.

I claim:

1. In a watch strap, two flexible strap members, holding means at a terminal of each of said members for attachment to a wrist watch, the opposite terminal portions of said members being detachably engageable with each other, and a flexible connecting member extending between and slidably mounted upon both of said strap members.

2. In a watch strap, two flexible strap members, holding means at a terminal of each of said members for attachment to a wrist watch, the opposite terminal portions of said members being detachably engageable with each other, a flexible connecting member extending between said strap members, loop means attached to the terminals of said connecting member and slidably mounted over said strap members, and stop means in the region of the terminal portions of the strap members for limiting the operative movement of said loop means over the strap members.

3. In a watch strap, two flexible strap members, holding means at a terminal of each of said members for attachment to a wrist watch, the opposite terminal portions of said members be-

ing detachably engageable with each other, a flexible connecting member extending between and engageable with the inner surfaces of said strap members, loop means attached to the terminals of said connecting member and slidably mounted over said strap members, and stop means in the region of the terminal portions of the strap members for limiting the operative movement of said loop means over the strap members.

4. In a watch strap, two flexible strap members, holding means at a terminal of each of said members for attachment to a wrist watch, the opposite terminal portions of said members being detachably engageable with each other, a flexible connecting member extending between said strap members, loop means attached to the terminals of said connecting member and slidably mounted over said strap members, and stop means in the region of the terminal portions of the strap members for limiting the operative movement of said loop means over the strap members, the stop means at one of the said detachably engageable terminal portions of the strap members comprising a raised ornamental member proportioned for abutment with the loop means on the adjacent terminal of the connecting member.

5. In a watch strap, two flexible strap members, holding means at a terminal of each of said members for attachment to a wrist watch, a buckle at the opposite terminal portion of one of said members, the corresponding terminal portion of the other of said members being detachably engageable with said buckle and containing a raised stop member, a flexible connecting member extending between and engageable with the inner surfaces of said strap members, loop means attached to the terminals of said connecting member and slidably mounted over said strap members, the said buckle and stop member being proportioned for abutment with the said loop means for holding them against disconnection, the relative proportions of the stop member and the buckle being such as to permit the stop member to operatively pass through the buckle.
